UNITED STATES PATENT OFFICE.

OSCAR BLAINE CLOW, OF TACOMA, WASHINGTON.

COMPOSITION SHINGLE.

Application filed April 26, 1927. Serial No. 186,733.

This invention relates to improvements in roofing, and more particularly to roofing shingles of the composition type designed to be laid in diagonal positions, that is, with the corners of the shingles extending in horizontal and vertical directions with their lower portions which are exposed to the weather bounded by downwardly converging, lateral edges which overlap the upper edge portions 10 of the shingles in the next lower course.

It is common practice in the manufacture of such shingles to slit, or notch, the edges of the shingles in various ways in order to provide for interlocking the shingles of one row 15 with those of the next lower row as a means of anchoring them in place and to insure better joints, but as a general rule, when the interlocking features and the joints are satisfactory, too much time is required to lay and 20 secure the shingles, and when the shingles are constructed for easy and quick laying, the anchoring feature is not satisfactory.

It is the principal object of the present invention to improve upon the means and method of interlocking the edges of shingles so 25 as to provide for easy and quick laying, while, at the same time, connections are provided that will preserve the relation between the shingles, which will prevent any curling 30 up of their lower edges and which will insure a roof that is substantially weather and leak proof.

It is also an object of the invention to provide a construction that not only provides for 35 secure attachment of the shingles, but also which presents a neat and attractive design and which is relatively inexpensive.

Specifically stated, the invention resides in the manner of slitting the edges of shingles 40 so as to provide for their being interlocked easily and quickly and to present a novel and attractive design.

In accomplishing the various objects of the invention, I have provided the improved details of construction, the preferred forms of 45 which are illustrated in the accompanying drawings, wherein—

Figure 1 is a plan view of a portion of a roof that is covered with shingles made and 50 laid in accordance with the present invention.

Figure 2 is a perspective view of a part of the same, particularly illustrating the interlocking features.

Figure 3 is a sectional detail taken on the 55 line 3—3 in Figure 2.

Referring more in detail to the drawings—

1 designates shingles embodied by the present invention, which are square in outline and formed of any suitable composition such as asphaltum impregnated fibrous material or the like. Such shingles are characterized by a certain degree of flexibility which renders it desirable and necessary to provide for securely anchoring their lowermost margins beneath the edges of the previously laid and fixed shingles so as to insure close and weather proof joints.

The present shingles are laid diagonally in horizontal courses, that is, with the corners of the shingles extending horizontally and vertically and with their lowermost corners disposed centrally within the angles formed by the converging edges of adjacent shingles of the next lower course.

Each shingle is provided at directly opposite points in its side edges and near its lowermost corner, as shown in Figures 1 and 2, with inwardly directed slits 2 which extend at right angles to the edges. The inner ends of these slits connect with slits 3 which extend downwardly and parallel with the edges of the shingles and which, in turn, merge into short, outwardly directed slits 4. In the present shingle, which is approximately 20 inches square, the slits 2 start at points approximately 4 inches from the lower corner and extend inwardly one and one-half inches. The slits 3 are each one inch long and extend toward the bottom edge of the shingle and the slits 4 are one-half inch long. However, I do not wish to be confined to these measurements since they are only mentioned for the purpose of better explanation.

The slits 2, 3 and 4, in the relation specified, define small anchoring tabs 5 which, as presently described, may be offset from the body of the shingle to permit their being projected beneath the edges of the shingles in a lower course for the purpose of anchoring the corner of the shingle to the roof.

Each of the shingles is also provided in the lower edges near the upper side corners with short, inwardly directed slits 6 formed at right angles to the edges, which are provided so as to permit the edges just below the slits to lie flat against the next lower shingle when the tabs of a superposed row of shingles are projected beneath their edges just above the slits.

Assuming that the shingles are so constructed, they are laid as follows:

First, the shingles of the lower row are

laid diagonally in a horizontal course and they are secured in place by nailing through their upper and opposite side corners. The shingles of the second course are then placed 5 in position with their lower, converging side edges overlapping the diverging upper edge portions of shingles of the lower course. The lower corners of shingles of the second course are disposed within the angles formed by the 10 lower edges of the adjacent shingles in the first course and the tab portions 5 are projected, when the shingles are drawn into place, beneath the edges of the shingles of the lower course to anchor the corners to the 15 roof. These shingles of the second course, after being drawn upwardly as far as will be permitted on account of the nailing through the side corners of the shingles of the first course, are also nailed through their top and 20 side corners. Each of the succeeding courses 25 are laid and secured in like manner.

With this construction and method of laying the shingles, a large anchor tab is provided at each side of the lower corner of each 25 shingle and each tab will be securely held

beneath the nailed edge of a shingle of the next lower course. The slits 4 and 6 in the shingles permit the material to be offset sufficiently that the joints will be closed to avoid any possible leakage. 20

Having thus described my invention, what I claim as new therein and desire to secure by Letters-Patent, is:

A roofing formed from a plurality of square shingles laid diagonally in horizontal, overlapped courses, each of said shingles being provided in the adjacent side edges thereof which bound its lower corner with slits that extend inwardly at right angles to the edges, then turn downwardly parallel 35 with the side edges, then outwardly perpendicular to but terminating within the edges and providing attached anchor tabs, which are projected beneath the side edges of the shingles in a lower course which are received 40 within the slits whereby the tabs are defined. 45

Signed at Tacoma, Washington, this 5th day of April, 1927.

OSCAR BLAINE CLOW.
